UNITED STATES PATENT OFFICE.

FRANKLIN M. DAMMON, OF NEW BEDFORD, MASSACHUSETTS.

PLAQUE.

SPECIFICATION forming part of Letters Patent No. 356,454, dated January 25, 1887.

Application filed September 30, 1886. Serial No. 214,910. (No model.)

To all whom it may concern:

Be it known that I, FRANKLIN M. DAMMON, a citizen of the United States, residing at New Bedford, in the county of Bristol and State of Massachusetts, have invented a new and novel device in Plaques, of which the following is a specification.

My invention consists in the combination, with a plaque, of a shell, as a novel ornamentation, and also as a cover or protection to a picture mounted on said plaque.

In the accompanying drawing, A is a plaque or card on which is mounted the shell B. When used for ornamentation only, there may be a number of shells attached to the plaque, according as taste or fancy may dictate. When used as a cover or protection for a picture, the shell is mounted on the plaque in the manner illustrated in the drawing, being hinged to the

plaque A by the hinge C, composed of cloth or other suitable material, one end of which hinge is concealed by the bow of ribbon d and the other end attached to the shell. The picture is mounted on the space covered by the shell.

By the use of a shell, in combination with a plaque, a new and beautiful effect is produced.

Having thus described my invention, what I claim, and desire to secure by Letters Patent, is—

The combination, with a plaque, of a shell, as a cover or protection to a picture mounted on said plaque.

FRANKLIN M. DAMMON.
